ATTORNEY

UNITED STATES PATENT OFFICE.

PATRICK J. EGAN, OF CARLETON, NEW BRUNSWICK, CANADA.

CAR-CO尤LING.

SPECIFICATION forming part of Letters Patent No. 406,203, dated July 2, 1889.

Application filed January 7, 1889. Serial No. 295,616. (No model.)

To all whom it may concern:

Be it known that I, PATRICK J. EGAN, of Carleton, in the county of St. John, Province of New Brunswick, and Dominion of Canada, 5 have invented a new and Improved Car-Coupling, of which the following is a full, clear, and exact description.

The object of the invention is to provide a new and improved car-coupling which is simple and durable in construction, very effective in operation, and adapted to couple two draw-heads of different heights.

The invention consists of certain parts and details and combination of the same, as will be 15 fully described hereinafter, and then pointed out in the claim.

Reference is to be had to the accompanying drawings, forming a part of this specification, in which similar letters of reference indicate 20 corresponding parts in all the figures.

Figure 1 is a sectional side elevation of the improvement as applied. Fig. 2 is a front elevation of the same. Fig. 3 is a perspective view of the coupling-link, and Fig. 4 is an enlarged sectional side elevation of part of the 25 coupling-link, pin-support, and coupling-pin.

The draw-head A is provided with the usual front opening B, into which is adapted to pass the end of a coupling-link C, adapted to be 30 engaged by the coupling-pin D, held to slide vertically in suitable bearings in the draw-head A and passing through the opening B. The coupling-pin D is held in an uppermost position by an elastic block E, secured in the 35 draw-head A directly behind pin D, and provided on its lower end with a shoulder F, which extends into the opening B and under the lower end of the coupling-pin D, as is plainly shown to the left of Fig. 1 and in Fig. 4. The block E is preferably made of rubber 40 in the shape illustrated in Fig. 4.

The coupling-link C is provided with a bridge G, made in the form of a spectacle-frame, as is plainly shown in Fig. 3. In the 45 middle of the bridge G is secured one end of a rope H, which extends upward and passes through a suitable opening in the top of the draw-head A. The rope H is secured at its upper end to a shaft I, extending transversely 50 on the front of the car and mounted to rotate in suitable bearings on the same. On each

outer end of the shaft I is secured a crank-arm J, for turning the said shaft I so as to wind the rope H on the shaft or unwind it from the same.

The operation is as follows: When the operator desires to couple two cars, he places the link C in one draw-head and moves the pin D into its lowermost position, as shown in Fig. 1. This is done by pressing the shoulder F of the elastic block E rearward, after which the pin D drops into place. The operator then moves the coupling-pin of the other draw-head into its uppermost position, so as to rest on the shoulder F of the elastic 65 block E, as shown to the left in Fig. 1. The coupling-link C is then raised or lowered by turning the crank-arms J so that the rope H is wound upon the shaft I or unwound from the same, whereby the link C is raised or 70 lowered to pass into the opening of the other draw-head. When the two draw-heads come together, the projecting end of the link presses against the shoulder F of the elastic block E, so that the shoulder F is moved rearward, and 75 the coupling-pin D is permitted to drop down, thereby locking the link in place on the other draw-head. Thus it will be seen that the coupling is effected automatically without a brakeman stepping between the cars. It will 80 further be seen that draw-heads of different heights—such as are found on empty and loaded cars—couple the same as draw-heads placed in a horizontal line, as the coupling-link can be conveniently raised or lowered to 85 engage the opposite draw-head.

Having thus described my invention, what I claim as new, and desire to secure by Letters Patent, is—

In a car-coupling, the combination, with a 90 draw-head provided with a pin-opening and a coupling-pin working therein, of the block E, of elastic material, rigidly secured in the draw-head in rear of and adjacent to the pin-opening, and provided with a shoulder, which 95 when the block is in its normal position is in alignment with the said pin-opening, substantially as described.

PATRICK J. EGAN.
